MELVIN L. STONE, OF PROVIDENCE, RHODE ISLAND, ASSIGNOR TO DRAPER CORPORATION, OF HOPEDALE, MASSACHUSETTS, A CORPORATION OF MAINE

AUTOMATICALLY-THREADING LOOM SHUTTLE

Application filed November 9, 1929. Serial No. 405,927.

This invention relates to automatically threading loom shuttles and is more particularly directed to the thread tensioning means whereby tension is exerted upon the thread during weaving and as the shuttle passes through the shed.

It is now the ordinary practice to provide automatically threading loom shuttles with thread tensioning means, but in order that the woven cloth shall present no defects, it is essential that the filling thread in the shuttle shall be equally tensioned throughout the weaving operation including the incoming filling which is supplied to the shuttle during replenishment. Should the incoming filling end not be tensioned in accordance with the tension exerted during subsequent weaving the cloth will present a defect and one of the objects of the present invention is to provide an automatically threading shuttle with thread tensioning members which may be moved from thread tensioning relation on replenishment of filling and be returned to their relative thread tensioning positions on completion of replenishment so that as the shuttle passes through the shed the new filling will be tensioned to the same degree as it is in subsequent weaving.

Filling replenishment looms are usually provided with a transerrer for supplying the shuttle with fresh filling and ejecting the filling carrier or bobbin previously in the shuttle, and advantage is taken of this fact in connection with the present invention by mounting upon the transerrer a controller, which, when the transerrer performs its function will cause the thread tensioning members to be moved in non-tensioning relation and on the return of the transerrer to idle position, permit the thread tensioning members to move relatively into thread tensioning position. Thus on replenishment the incoming filling may be operatively related to the tensioning members and on completion of replenishment the tensioning members will unerringly act upon the thread to tension it to the same degree that it is tensioned during subsequent weaving.

In the tensioning devices heretofore ordinarily employed dependence is placed upon

the swirling action of the thread as the shuttle is picked to pass the thread into control of the tensioning members, but in accordance with the present invention the incoming filling thread passes into control of the thread tensioning members before the shuttle is picked, and as contributing to this end the thread is positively depressed on replenishment of filling so that it becomes at once operatively related to the tensioning members before the shuttle is moved from the shuttle box.

The invention and novel features thereof will best be made clear from the following description and accompanying drawings of one good form thereof, it being understood that variations of details may be made within the true scope of the invention as pointed out by the claims.

In the drawings:—

Fig. 1 is a perspective view of parts at the replenishing side of the loom and shuttle in the replenishment box provided with the present invention; and

Fig. 2 is a cross section through the shuttle on the line 2—2 of Fig. 3; and

Fig. 3 is a plan view of the delivery end of the shuttle showing features of the present invention; and

Fig. 4 is a similar view to that of Fig. 3 showing the tensioning members in thread tensioning relation, and

Fig. 5 is a longitudinal section on the line 5—5 of Fig. 4.

The replenishing shuttle box 1 may be of usual construction through which the ejected filling carrier or bobbin may pass during replenishment of filling, and associated with the replenishing shuttle box is a transerrer 3 which may be of usual construction and operated as well understood in the art to transfer a fresh filling carrier 4 from a source of supply to the shuttle on call for replenishment of filling.

The shuttle 5 is provided as usual with the bobbin chamber 6 and the side delivery eye 7 and forward of the bobbin chamber the shuttle has a threading block 8 whereby the shuttle becomes automatically threaded after replenishment as the shuttle is picked first

in one direction and then in the opposite direction. The threading block 8 may be of any of the well known usual types and is secured in the shuttle by the transversely extending bolt 9 which also may be as heretofore employed, the construction being such that the incoming filling *a* will pass into the longitudinal thread passage 10 on the first pick of the shuttle following replenishment and as the shuttle returns to the replenishing box it will be completely threaded as usual.

As hereinbefore suggested it is essential that the incoming filling shall be tensioned on the first pick of the shuttle following replenishment and means are consequently employed to move the thread tensioning members relatively out of the thread tensioning position as the transerrer supplies fresh filling to the shuttle and on completion of replenishment the threaded tensioning members take control of the incoming thread and apply the same tension thereto on the first pick of the shuttle as in subsequent weaving.

The tensioning members may be variously contrived in the scope of the present invention but as herein shown the two tensioning members 11 and 12 consist of plate-like elements mounted upon the securing bolt 9 through the medium of spring arms 13 and 14 which extend between the wood of the shuttle as at 15 and the outer side walls of the threading block as more clearly indicated by dotted lines in Figs. 3 and 4. The spring arms 13 and 14 preferably extend forward of the bolt 9 which passes through each of them and thus afford extended bearings for the front end portions of such arms.

The tensioning members 11 and 12 have thread engaging elements 16 which, in the present instance of the invention, extend upwardly from the tensioning members 11 and 12 so that when the tensioning members are in thread tensioning position as indicated by Fig. 4 the thread engaging elements 16 will cause the thread to take a certain course about the upwardly extending thread engaging elements and thereby impart to the thread a slip grip friction.

From the construction thus far described it will be apparent that the thread tensioning members are mounted for yielding movement relatively into and out of thread tensioning position, and normally held in such position and moved to such position by the spring arms 13 and 14.

The transerrer 3 has as usual the arm 17 extending therefrom for the support of a bobbin engaging tip member 18 so that on replenishment of filling both the head and tip portions of bobbin are moved by the transerrer into the bobbin chamber.

In accordance with the present invention the thread tensioning members are to be moved relatively from thread tensioning re-

lationship on replenishment of filling and in the present instance of the invention the transerrer has connected thereto a controller which travels with the transerrer on replenishment of filling to move the tensioning position as indicated in Fig. 3.

In the present instance of the invention the bobbin tip engaging member 18 of the transerrer has adjustably mounted thereon a bracket 19 which may be secured in adjusted position by means of a bolt 20 which passes through a slot 21 formed in the bobbin tip engaging member.

The bracket 19 has a bearing portion 22 in which is mounted the controller 23 and the lower end portion of the controller is provided with a head 24 so positioned with relation to the thread tensioning members that on operative movement of the transerrer the controller head will engage portions of the thread tensioning members and move them relatively from thread tensioning position.

In order that the controller may have yielding movement in case of obstruction a spring 25 is interposed between the head 24 of the controller and the bearing 22, as indicated in Fig. 1 and a pin 26 extends through the bearing 22 and a vertical slot 27 formed in the controller to maintain the head 24 of the controller in its proper rotative relation with the thread tensioning members. The upper portion of the controller may be threaded as at 28 and its downward movement under the impulse of the spring 25 may be limited by adjusting nuts 29.

As shown the thread tensioning members are provided with portions 30 which preferably converge downwardly in the path of movement of the head 24 of the controller with the result that as the controller moves downwardly with the transerrer it will move the thread tensioning members relatively from their thread tensioning relation.

The head 24 of the controller is preferably formed as a wedge the sides of which also converge downwardly as indicated at 31 Fig. 2, the result being that as the controller moves downwardly with the transerrer the movement of the thread tensioning members from their thread tensioning position is effected with a somewhat more gradual movement than would otherwise be the case.

In filling replenishing looms it is the common practice to secure the end of the incoming filling to a fixed point, sometimes on the hopper or magazine so that as the fresh supply of filling is transferred to the shuttle the incoming filling *a* will extend from the fresh filling carrier longitudinally along the thread passage of the shuttle and in most instances will be located between the non-tensioning position of the thread tensioning members on replenishment. It is preferable, however, to insure that the incoming

filling shall be relatively positioned for the action of the tensioning members, and to this end the present invention provides a thread positioner or depressor for positively moving the incoming filling into its cooperative relation with the thread tensioning members while they are in non-thread tensioning position. As a convenient means of thus depressing and positioning the incoming thread, the head 24 of the controller is provided with a recess 32 the walls of which may be converged upwardly with the result that as the controller moves with the transferrer on replenishment of filling it will straddle or engage the incoming filling ^a and by a further downward movement of the controller will positively carry or depress the incoming filling between the tensioning members, so that upon movement of the controller and transferrer to idle position and a consequent movement of the thread tensioning members to thread tensioning position the incoming filling will be placed in control of the tensioning members as indicated in Fig. 4.

In the present instance of the invention both of the thread tensioning members are mounted for movement horizontally from thread tensioning position to open a passage way between the thread engaging element 16 for the incoming filling thread, and to prevent the incoming filling thread from passing downwardly below the thread tensioning members, each of said members is provided with thread supporting fingers 33 disposed opposite to recesses 34 in the companion thread tensioning member, and such fingers and recesses are proportioned such that they provide a support for the incoming filling thread in all positions of the thread tensioning members.

The thread engaging elements 16, which as hereinbefore stated projected upwardly from the tensioning members 11 and 12 in staggered relation, are preferably provided with in-turned end portions 35, with the result that once the incoming filling has been positioned for the action of the thread engaging elements, and the tensioning members have been moved into tensioning relation, all escape of the filling from between the thread engaging elements is avoided.

When the transferrer is actuated to transfer a fresh supply of filling to the shuttle while the latter is in the replenishing shuttle box, the controller, which moves with the transferrer separates the thread tensioning members for the reception of the incoming filling between the thread engaging elements, and the thread depressor acts to depress the thread and insure that it shall be related to the thread tensioning members such that when the controller moves to its idle position with the transferrer the incoming thread will be subjected to tension as the shuttle is

picked and passes through the shed and such tension will remain the same during subsequent weaving.

What is claimed is:

1. An automatically threading loom shuttle having a bobbin chamber and side delivery eye, thread tensioning members mounted for movement into and out of thread tensioning relation, a transferrer for supplying the shuttle with fresh filling thread, means carried by the transferrer for moving the tensioning members relatively from thread tensioning relation by downward movement of the transferrer during replenishment of filling, and permitting return of the tensioning members relatively to thread tensioning relation as the transferrer moves to idle position that the incoming filling may be tensioned as the shuttle passes through the shed on the first pick of the shuttle following replenishment of filling. ⁷⁰

2. An automatically threading loom shuttle having a bobbin chamber and side delivery eye, thread tensioning members mounted for movement into and out of thread tensioning relation, a transferrer for supplying the shuttle with fresh filling thread, means connected to the transferrer for moving the tensioning members relatively from thread tensioning relation during replenishment of filling, a thread positioner for moving the incoming filling thread into position for the action of the tensioning members, and permitting return of the tensioning members relatively to thread tensioning relation as the transferrer and said connected means move to their idle position that the incoming filling may be tensioned on the first pick of the shuttle following replenishment of filling. ⁹⁰

3. An automatically threading loom shuttle having a bobbin chamber and side delivery eye, thread tensioning members between the bobbin chamber and side delivery eye for applying tension to the thread as the shuttle passes through the shed, a transferrer for supplying the shuttle with fresh filling thread, a controller mounted on the transferrer for moving the tensioning members relatively from thread tensioning relation by the downward movement of the transferrer that the incoming filling thread may be laid in operative relation with the tensioning members, and permitting return of the tensioning members to tensioning position as the controller moves separately with the transferrer to idle position that the incoming filling may be tensioned as the shuttle passes through the shed on the first pick following replenishment of filling. ¹⁰⁵

4. An automatically threading loom shuttle having a bobbin chamber and side delivery eye, thread tensioning members between the bobbin chamber and side delivery eye for applying tension to the thread as the shuttle passes through the shed, a transferrer for ¹¹⁰ ¹¹⁵ ¹²⁰ ¹²⁵ ¹³⁰

supplying the shuttle with fresh filling thread, an arm extending from the trans-
ferrer towards the outer end of the shuttle
box, a controller mounted on the arm for
5 moving the tensioning members relatively
from thread tensioning relation as the trans-
ferrer replenishes the filling that the incom-
ing filling thread may be laid in operative
relation with the tensioning members and
10 permitting return of the tensioning members
to tensioning relation as the controller moves
upwardly to idle position, and means for en-
gaging and depressing the incoming filling
into operative relation with the tensioning
15 members while the tensioning members are in
nontensioning relation.

5. An automatically threading loom shut-
tle having thread tensioning members to ap-
ply tension on the thread as the shuttle passes
20 through the shed, a transerrer for supply-
ing the shuttle with fresh filling, a controller
mounted on the transerrer for moving the
tensioning members from thread tensioning
25 relation as the transerrer replenishes the
filling, means acting on the incoming filling
thread to depress and position it for the ac-
tion of the tensioning members before the
shuttle is picked, and permitting return of
30 the tensioning members to thread tensioning
position as the controller moves to idle posi-
tion with the transerrer that the incoming
thread may be engaged by the tensioning
members.

6. An automatically threading loom shut-
tle having thread tensioning members, a
35 transerrer for supplying the shuttle with
fresh filling, a controller mounted on the
transerrer for downward movement there-
with to move the tensioning members from
40 thread tensioning relation as the transerrer
supplies the shuttle with fresh filling, and
permitting return of the tensioning members
to thread tensioning relation as the controller
45 moves to idle position and a thread depressor
carried by the controller for depressing the
incoming filling into operative relation with
the tensioning members.

7. An automatically threading loom shut-
tle having thread tensioning members mount-
50 ed for movement relatively into and out of
thread tensioning relation, a transerrer for
supplying the shuttle with fresh filling, a
controller mounted on the transerrer and
having a part that enters between the ten-
55 sioning members to separate them as the
transerrer replenishes the filling that the
incoming thread may pass between the sep-
arated tensioning members, and permitting
the tensioning members to move into thread
60 tensioning relation as the controller is with-
drawn from between the tensioning members
on completion of replenishment of filling.

8. An automatically threading loom shut-
tle having thread tensioning members mount-
65 ed for movement relatively into and out of

thread tensioning relation, a transerrer for
supplying the shuttle with fresh filling, a
controller mounted on the transerrer and
having a part that enters between the ten-
70 sioning members to separate them as the
transerrer replenishes the filling and pro-
vided with a thread depressor to depress the
incoming thread that the incoming thread
may pass between the separated tensioning
75 members, and permitting return of the ten-
sioning members into thread tensioning rela-
tion as the controller is withdrawn from be-
tween the tensioning members on completion
of replenishment of filling.

9. An automatically threading loom shut-
tle having thread tensioning members mount-
ed for movement into and out of thread ten-
sioning relation, a transerrer, a controller
connected for movement with the transerrer
and having a wedge portion to separate the
80 tensioning members as the transerrer re-
plenishes the filling and provided with a
thread depressor to depress the incoming
filling thread between the separated tension-
ing members, and permitting return of the
85 tensioning members into thread tensioning
relation as the wedge is withdrawn from be-
tween the tensioning members.

10. An automatically threading loom shut-
tle having cooperating thread tensioning
members relatively movable in a substan-
tially horizontal plane into and out of thread
90 tensioning position, a transerrer, a con-
troller mounted on the transerrer for rela-
tively moving the tensioning members into
non-tensioning relation as the transerrer re-
plenishes the filling and having a thread de-
95 pressor to push the incoming filling into co-
operating relation with the non-tensioning
positioned tensioning members, and permit-
ting return of the tensioning members into
tensioning position upon the incoming filling
100 thread when the controller is moved up-
wardly with the transerrer that the incom-
ing filling may be tensioned as the shuttle
105 passes through the shed on the first pick of
the shuttle following replenishment.

11. An automatically threading loom shut-
tle having thread tensioning members pro-
vided with thread engaging elements and
110 mounted for relative movement into and out
of thread tensioning position, thread sup-
porting fingers extending from the tension-
ing members in overlapping horizontal rela-
tion adapted to support the thread in all rela-
tive positions of the tensioning members, a
115 transerrer, a controller connected for down-
ward movement with the transerrer for mov-
ing the tensioning members relatively from
thread tensioning relation on replenishment
120 of filling and permit the incoming thread to
pass into operative relation with the thread
engaging elements, and permitting return
of the tensioning members into thread ten-
sioning position on the incoming thread as
125

the controller again moves upwardly to idle position that the incoming thread may be tensioned as the shuttle passes through the shed on the first pick of the shuttle following replenishment.

- 5 12. An automatically threading loom shuttle having thread tensioning members mounted for movement into and out of thread tensioning relation, a transerrer, a controller connected for movement with the transerrer to effect relative movement of the tensioning members into non-tensioning position on replenishment of filling and permitting relative movement of the tensioning members into
10 15 thread tensioning relation on completion of filling replenishment that the incoming filling may be tensioned as the shuttle passes through the shed on the first pick following replenishment, and an incoming thread de-
20 pressor for placing the incoming thread in operative relation with the tensioning members when they are in non-tensioning position.

15 In testimony whereof, I have signed my name to this specification.
